UNITED STATES PATENT OFFICE.

SILAS ISAAC PHILLIPS, OF DELAVAN, WISCONSIN.

PEN AND PENCIL HOLDER.

Application filed July 3, 1923. Serial No. 649,310.

To all whom it may concern:

Be it known that I, SILAS ISAAC PHILLIPS, a citizen of the United States, residing at Delavan, in the county of Walworth and 5 State of Wisconsin, have invented a new and useful Pen and Pencil Holder, of which the following is a specification.

This invention relates to article holders and more particularly holders especially designed for supporting pens and pencils or the like, the primary object of the invention being to provide means wherein a pen or pencil may be supported in the pocket of the user eliminating any possibility of the pen 10 or pencil becoming accidentally displaced.

Another object of the invention is to provide a device of this character which may be stamped from a sheet of flexible metal, the metal being curved or bent to grip a pen or 15 pencil supported therein.

Another object of the invention is to provide means for securing the holder in the pocket of the user.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed, may be made within the scope of what is claimed, without departing from the spirit of the invention.

Referring to the drawing:

Figure 1 is a front elevational view of a 30 holder constructed in accordance with the invention, a portion thereof being broken away.

Figure 2 is a sectional view taken on line 2-2 of Figure 1.

Figure 3 is a perspective view of the modified form.

As shown by the drawing, the holder is in the form of a sheet metal base 15 formed with a curved extremity 16, which curved 40 extremity cooperates with the band 17, that overlies the face of the base to grip a pen or pencil positioned under the band.

Curved fingers 18 are stamped from the base 15 and are curved in the direction of 45 the band 17 to set up a binding action be-

tween the band and fingers to grip a pen or pencil passed under the band. In this form of the invention, it is also contemplated to use a clasp for securing the device in the pocket of the user. 55

In the form of the invention as shown by Figure 2 of the drawings, the device includes a length of sheet metal bent upon itself, to provide opposed jaws 19, each of which being formed with a plurality of 60 curved portions 20 that cooperate, when the jaws are in positions as shown by Figure 3 to clamp articles such as pencils or the like therebetween.

A clasp 21 is also secured to the device in 65 order that the same may be positioned in the pocket of the user against displacement.

What is claimed as new is:—

1. In a holder, a body portion having one edge thereof curved inwardly, a band secured to the body portion adjacent to the opposite edge thereof, and said band adapted to engage an article positioned thereunder and set up a binding action between the article and the inwardly curved end of 75 the body portion.

2. In a holder, a body portion, a band overlying the body portion and spaced therefrom, said body portion having fingers disposed under the band, said fingers adapted 80 to set up a binding action with the band to hold an article supported therebetween, and said body portion having one end thereof curved inwardly.

3. In a holder, a body portion, a band secured to the body portion and overlying a portion thereof in spaced relation therewith, spring fingers stamped from the body portion and extending towards the band directly under the band, and said spring fingers 90 adapted to set up a binding action between the band and an article positioned thereunder.

In testimony that I claim the foregoing as my own, I have hereto affixed my signature in the presence of two witnesses. 95

SILAS ISAAC PHILLIPS.
